LIGHTING FIXTURE

Carl Moser, Larchmont, N. Y., assignor to Lightolier,
Incorporated, a corporation of New York

Application December 18, 1956, Serial No. 44,239

Term of patent 14 years

(Cl. D48—23)

Fig. 1 is a perspective view of the lighting fixture showing my new design,

Fig. 2 is a bottom plan view,

Fig. 3 is a side elevational view thereof, and

Fig. 4 is a perspective view of the reflector partly in cross section.

The characteristic feature of the design for the lighting fixture disclosed, resides in the inverted bowl-shaped reflector having in combination therewith a central hub with arms radiating therefrom to the inner periphery of the reflector, as shown.

I claim:

The ornamental design for a lighting fixture, substantially as shown and described.
